99,101

DESIGN FOR AN AUTOMOBILE HEATER

Carl H. Will, Minneapolis, Minn., assignor to
Tropic-Aire, Incorporated, Minneapolis, Minn.,
a corporation of Delaware

Application November 1, 1935, Serial No. 59,323

Term of patent 3½ years

To all whom it may concern:

Be it known that I, Carl H. Will, a citizen of the United States, residing at Minneapolis, in the county of Hennepin and State of Minnesota, have invented a new, original, and ornamental Design for Automobile Heaters, of which the following is a specification, reference being had to the accompanying drawing, forming part thereof, and in which the figure is a perspective view of the heater.

The characteristic feature of my design resides in the series of vertically disposed spaced ribs extending from the top to bottom of the heater shell, exposing the rectangular section of the radiator core between the shutters.

I claim:

The ornamental design for an automobile heater, substantially as shown and described.

Minneapolis, Minn., Oct. 26, 1935.

CARL H. WILL.
